Patented Dec. 10, 1957

181,658

SET OF PLAYING CARDS

Albert L. King, Decatur, Tex.

Application October 16, 1956, Serial No. 43,372

Term of patent 7 years

(Cl. D34—13)

Figure 1 is a front elevational view of one of the cards forming my set, the "two" to "nine" cards inclusive, being identical therewith, except for the numeral of value,

Figure 2 is a rear elevational view of one of the cards, the back of all of the cards having the same appearance,

Figures 3 through 6 are front elevational views of the face cards, and

Figure 7 is a front elevational view of the joker.

I claim:

The ornamental design for a set of playing cards, as shown and described.
